US00D901233S

(12) **United States Design Patent** (10) **Patent No.:** **US D901,233 S**
(45) **Date of Patent:** **** Nov. 10, 2020**

(54) **MEAT GRINDER**

(71) Applicant: **GUANGZHOU LIVING
HARDWARE AND PLASTIC
MANUFACTURING CO., LTD,**
Guangzhou (CN)

(72) Inventor: **Shuyuan Lin**, Jiangmen (CN)

(73) Assignee: **GUANGZHOU LIVING
HARDWARE AND PLASTIC
MANUFACTURING CO., LTD,**
Guangzhou (CN)

(**) Term: **15 Years**

(21) Appl. No.: **29/698,084**

(22) Filed: **Jul. 15, 2019**

(51) LOC (12) Cl. **31-00**

CLAIM

The ornamental design for a meat grinder, as shown and described.

DESCRIPTION

FIG. 1 is a perspective view of a meat grinder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded view of the meat grinder showing the cup separate from the main body.

The broken lines in the drawings depict portions of the meat grinder that form no part of the claimed design.

1 Claim, 9 Drawing Sheets
